SAFETY ATTACHMENT FOR DRILLING MACHINES

Ely F. Gory, Wilsonville, Ill.

Application February 2, 1934, Serial No. 709,528

10 Claims. (Cl. 255—47)

This invention relates to a safety attachment for drilling machines, preferably of the coal or rock drilling type the general object of the invention being to provide a telescopic cover for the threaded part of the drilling shaft or thread bar of the machine which prevents clothing of a workman getting caught in the threaded shaft, as often occurs, and which generally results in serious injury to the workman.

10 This invention also consists in certain other features of construction and in the combination and arrangement of the several parts, to be hereinafter fully described, illustrated in the accompanying drawings and specifically pointed out in the appended claims.

15 In describing the invention in detail, reference will be had to the accompanying drawings wherein like characters denote like or corresponding parts throughout the several figures, and in which:

20 Fig. 1 is a view of a drilling machine, showing the invention in use thereon;

Fig. 2 is a sectional view showing how the invention is supported from the machine;

25 Fig. 3 is a view, partly in section, showing how the telescopic sleeve members engage each other and also engage parts of the drilling shaft or thread bar;

Fig. 4 is a view of the extensible slotted tube or sleeve, partially in section;

30 Fig. 5 is a view of one of the circular plates; Fig. 6 is a sectional view through one of the plates;

Fig. 7 is a plan view of the drilling shaft or thread bar of the machine, portions of the length thereof broken away;

Fig. 8 is a face view of the other plate;

35 Figs. 9 and 10 are views showing the rod members for connecting the two plates together, and

Fig. 11 is an end view of the hub member.

40 In the drawings, the letter A indicates the drilling machine which includes the usual drill shaft or thread bar *a*, the housing *b* which encloses the driving mechanism therefor, and the preferably separable box or nut *c* which normally functions to feed said shaft through said machine.

45 In carrying out my invention I provide a plate 1 which is connected by bolts to the housing *b* and a second plate 2 which is located in rear of the box or nut *c* and is connected to the plate 1 by rods 3 having threaded reduced ends engaging threaded holes in said plates. Spacers 4 are provided for one of the bolts, see Figs. 1 and 2.

50 A hub 5 has its inner end fitting in a countersink in the plate 2 and said hub is bolted to said plate 2 and is internally screw threaded to receive the threaded end of a tube or sleeve 6 which is locked in the hub by a set screw 7. A second extensible tube or sleeve 8 has a sliding telescopic 55 fit in the tube 6 and this tube 8 is formed with a

longitudinally extending slot 9 in the length thereof for receiving the inner end of a screw 10 passing through a threaded hole in the outer end of the tube 6, see Fig. 3. The outer end of the tube 8 has a reduced bore which, at its junction with the large part of said bore of the tube 8, forms a shoulder for engagement by a suitably fixed collar 11 provided at the outer end of the threaded portion of the drilling shaft or thread bar *a*.

10 It will thus be seen that the tube 6 is firmly supported from the drilling machine and slidably supports the telescoping tube 8, the drilling shaft or thread bar *a* passing through both tubes and as the drilling shaft or thread bar *a* is rotatively fed outwardly, its collar 11, engaging or abutting the shoulder at the outer end of the tube 8, will cause the tube 8 to move outwardly with the shaft and thus the threaded part of the shaft is covered by the telescopic tubes 6 and 8 at all times and there is no danger of the clothing of a workman getting caught in the threads of the shaft, which often happens, and which might injure or kill an attending workman.

15 While the drawings show the tube 8 provided with an elongated slot 9 for receiving the end of the screw 10 which limits the outward movement of the tube 8, this slot is not absolutely necessary as other suitable means may be provided for limiting the outward movement of the tube 8.

20 When the invention is used on the type of machine illustrated in Figs. 1 and 2, the lower bolt 3 acts as a hinge support for the two preferably separable and threaded parts of the box or nut *c* through which is adapted to be fed the threaded shaft *a* of the machine. In this case, the bushings or spacers 4 are placed at the inner ends of the lower rod 3, as shown in Fig. 2, and act to hold the hinge members of the box or nut *c* in proper alignment on said rod. The groove in the plate 1, see Figs. 2 and 5, permits the threaded members of the box or nut *c* to open only to the limit of such groove and keeps the nut or box *c* in proper alignment with the drilling shaft *a*.

25 It will be understood, however, that other means for attaching the invention to the machine may be used and in accordance with the particular types of machines on which the invention is used.

30 In the several figures, particularly Figs. 1 and 3, the shaft *a* is illustrated in an advanced or extended drilling position with the associated tubes or sleeves 6 and 8 covering and protecting the threaded portions of said shaft. In Fig. 1 35 the usual chuck or socket is shown attached to the forward end of the drilling shaft *a* to which is adapted to be fitted a suitable drilling tool, not shown.

35 It will be understood that the shaft *a* can be 40

returned from its illustrated advanced or extended position either by reversing the driving mechanism of the drilling machine or by opening the separable members of the box or nut c 5 and manually moving the shaft *a* backwards to the desired location. In either of these adjustment operations, it will be further understood that the extensible tube or sleeve 8 is caused to travel with the return movement of the shaft *a* 10 by reason of the chuck or socket or other suitable element on the forward end of said shaft *a* abutting the forward end of the tube 8, thereby causing said tube to telescope in its backward movement in said tube 6. In other words, 15 whether the shaft *a* is extended or not, the threaded portions of said shaft *a* are at all times protected against contact by the clothing or body of an attending workman by the tubes or sleeves 6 and 8, thereby making the machine practically 20 accident-proof to those who operate the machine or in close proximity to it.

It is thought from the foregoing description that the advantages and novel features of the invention will be readily apparent.

25 It is to be understood that changes may be made in the construction and in the combination and arrangement of the several parts, provided that such changes fall within the scope of the appended claims.

30 What I claim is:—

1. In a drilling machine including a rotatable drill shaft adapted for forward and backward movement through said machine, a threaded portion on said shaft, an extensible sleeve adapted 35 for coaction with said shaft in its movements through the machine and for enclosing the threaded portion thereof in such movements, and means for supporting said sleeve from a part of the machine.

40 2. In a drilling machine including its drill shaft provided with a threaded portion, a plate attached to a part of the machine, a second plate spaced from the first plate, the two plates receiving a feeding member for the shaft between 45 them, means for connecting the two plates together, a hub carried by the second plate, a tube fitting in the hub, a second tube telescoping into the first tube, the shaft passing through the two plates, the hub and the two tubes enclosing the 50 threaded portion of the shaft, and a collar at the outer end of the threaded part of the shaft for engaging a part of the second tube to cause movement of the second tube by the shaft.

55 3. In a drilling machine including a rotatable drill shaft having a threaded portion, means for imparting extending movement to said shaft, a stationary member enclosing a threaded portion of said shaft, means for supporting said member from said machine and an extensible member supported by said first member for enclosing an extended threaded portion of said shaft when said shaft is extended through said members.

60 4. In a drilling machine including a rotatable drill shaft having a threaded portion, means for extending said shaft through said machine, a stationary member enclosing a threaded portion of said shaft, means for supporting said member from said machine and a telescopic member slidably arranged within said first member for enclosing an extended threaded portion of said shaft

when said shaft is extended through said machine.

5 5. In a drilling machine, in combination, a threaded drill shaft, driving mechanism for imparting rotation to said shaft, a feeding member arranged for threaded engagement with said shaft to rotatively advance said shaft through said machine, a support, telescopic members carried by said support for enclosing the threads of said shaft, means on said shaft adapted to engage 10 the inner of said telescopic members upon advance movement of said shaft whereby said member is extended with the advance movement of said shaft to enclose the extended threaded area of said shaft.

15 6. In a drilling machine, in combination, a housing, a rotatable drill shaft adapted for movement through said housing, a driving means for said shaft, a stationary sleeve associated with said housing adapted to receive said shaft, an extensible 20 sleeve supported by said stationary sleeve adapted to receive said shaft and be coactable therewith, and means for extending said extensible sleeve with said shaft upon movement thereof through said housing and said stationary sleeve.

25 7. In a drilling machine, in combination, a housing, a rotatable drill shaft adapted for forward and backward movement through said housing, a driving means for said shaft, a stationary sleeve associated with said housing adapted to receive and enclose said shaft, an extensible sleeve supported by said stationary sleeve adapted to receive and enclose said shaft and arranged for telescopic relation with said stationary sleeve, means 30 for extending said extensible sleeve upon forward movement of said shaft through said housing and said stationary sleeve, and means for restoring said extended sleeve in retracted telescoped relation with said stationary sleeve upon backward movement of said shaft through said housing 35 and said stationary sleeve.

40 8. A safety attachment for drilling machines comprising a support, a protecting sleeve fixedly secured to said support and extended therefrom, an extensible protecting sleeve axially disposed 45 for telescopic relation with said first sleeve, and a rotatable drill shaft adapted upon forward movement through said support and said first mentioned sleeve to impart a forward extensible movement to said extensible sleeve.

45 9. A safety attachment for drilling machines comprising a support, a protecting sleeve fixedly secured to said support and extended therefrom, an extensible protecting sleeve axially disposed 50 for telescopic relation with said first sleeve, and a rotatable drill shaft adapted upon forward and backward movement through said support and said first mentioned sleeve to impart like movement to said extensible sleeve.

55 10. A safety attachment for drilling machines comprising a support, a protecting sleeve fixedly secured to said support and extended therefrom, an extensible protecting sleeve axially disposed 60 for telescopic relation with said first sleeve, a rotatable drill shaft adapted for movement through said support and sleeves, and means on said shaft engageable with said extensible sleeve upon movement therethrough to impart axial movement to said extensible sleeve with said shaft.

70 ELY F. GORY.
